UNITED STATES PATENT OFFICE.

DAVID BOYD, OF LOUISVILLE, KENTUCKY.

FLUE-CLEANER.

SPECIFICATION forming part of Letters Patent No. 698,174, dated April 22, 1902.

Application filed July 29, 1901. Serial No. 70,164. (No model.)

To all whom it may concern:

Be it known that I, DAVID BOYD, a citizen of the United States, residing at Louisville, in the county of Jefferson and State of Kentucky, have invented a new and useful Flue-Cleaner, of which the following is a specification.

My invention relates to certain improvements in flue-cleaners, and has for its object to provide a device of this construction which will quickly and thoroughly effect the removal of soot and scale from the interior of boiler tubes and flues, as more particularly described hereinafter.

15 In the accompanying drawings, Figure 1 is an elevation, partly in section, of a flue-cleaner constructed and arranged in accordance with my invention; and Fig. 2 is a perspective view of the same.

20 In carrying out my invention I propose to employ at the forward end of the tube or flue a device for creating a partial vacuum, and so inducing the flow of a current of air through the tube to remove the accumulations of soot 25 or scale. In order to loosen the deposit and more thoroughly cleanse the flues, I employ one or more cleaning-wheels having suitable means for effecting their reciprocation from end to end of the flue, such wheels being so 30 mounted and constructed as to be rapidly revolved under the influence of the air-current.

Referring to the drawings, 1 represents a curved discharge-pipe having an upwardly-extending nozzle 2 and a horizontally-extending annular portion 3, adapted to enter the end of the tube, this annular portion being preferably of a size equal to the smaller-size tubes and adapted to fit snugly therein, suitable bushings or collars 4 being employed 35 when it is desired to fit the same within the end of a tube of greater diameter.

Within the nozzle 2 and having its center coincident with the center of said nozzle is a small steam-nozzle 5, the lower portion of 40 which is in communication with a steam-pipe 6, connected by a flexible pipe or hose 7 to the boiler, the quantity of steam and the area of the discharge-nozzle 5 being such as to cause the device to operate on the principle of an 45 injector and induce the flow of a current of air from the rear to the front of the flue or tube. The steam-pipe 7 is connected to a pipe

8 of some considerable length and forming a handle by which the device may be operated at a convenient distance from the tube-sheet of 55 the boiler, the weight of the apparatus being counterbalanced by a weight 9, secured by a rope or wire 10 to the handle portion 8 and passing over a sheave 11, which may be supported at the upper portion of the boiler or 60 from the ceiling of the fire-room.

The dirt-loosening devices comprise one or more wheels 12, secured to a hub 13, which may freely rotate on a central shaft or axis 14, which extends out through the casing 1 and 65 has its outer end guided in a suitable opening in a handle 15, depending from the steam-pipe. This shaft or axis 14 forms an operating-rod for effecting the reciprocation of the wheels 12 from end to end of the flue, such 70 wheels being guided and held centrally within the flue by guides 16, formed of radially-arranged plates 17, clamped to the shaft or axis 14, the radial projection of such plates being greater at the ends adjacent to the wheels 12 75 than at the opposite ends to provide for their ready insertion within the tubes.

Each wheel 12 is formed of a series of radiating blades of gradually-increasing width from the hub to the circumference and inclined at such an angle that the current of air passing through the tube will cause them to rapidly revolve and by contact with the inner surface of the tube displace any soot or 80 scale which may have formed.

In operation the annular end 3 of the casing 1 and the cleaning wheel or wheels 12 are inserted within the end of the tube to be cleaned, the nozzle portion being turned up in the line of the chimney-flue. On introduction of steam through the nozzle 5 a vacuum will be created at the forward end of the tube, and the flow of a current of air will be induced, which will cause wheels 12 to revolve, such wheels meantime being moved back and 95 forth from end to end of the tube by the operating-rod 14 until all parts of the tube have been cleaned, the loosened dirt and scale being carried by the air-current and discharged through the nozzle 2.

It will be understood that various modifications in the sizes, proportions, and details of structure may be made without departing 100 from my invention.

Having thus described my invention, what I claim is—

1. A flue-cleaning device comprising in combination, an upwardly-curved discharge nozzle or pipe having one of its ends adapted to be temporarily secured within the end of the flue, a steam-nozzle located within the discharge end of the pipe and adapted to create a partial vacuum at the end of the flue, a rod passing through the wall of said tube and of a length greater than that of the flue to be cleaned, and a rotatable sealing-wheel mounted on said rod and having vanes adapted to be revolved by the current of air induced through the flue, substantially as specified.
2. A flue-cleaning device, comprising a curved discharge-pipe having an annular end adapted to fit within the end of the flue and a nozzle-shaped discharge end, a steam-sup-

ply pipe, a discharge-nozzle communicating therewith and situated within the discharge-pipe, a counterbalancing-weight connected to said steam-pipe, a shaft or axis 14 extending through the casing of the discharge-pipe into the flue to be cleaned, a pair of vaned wheels mounted on said axis and adapted to be revolved by a current of air passing through the tube and tapering guiding-plates clamped to said axis on opposite sides of the pair of wheels, substantially as specified.

In testimony that I claim the foregoing as my own I have hereto affixed my signature in the presence of two witnesses.

DAVID BOYD.
